UNITED STATES PATENT OFFICE.

TONY ALEXANDER, OF BROOKHAVEN, MISSISSIPPI.

LEVEL.

No. 812,251.

Specification of Letters Patent.

Patented Feb. 13, 1906.

Application filed March 25, 1905. Serial No. 252,076.

To all whom it may concern:

Be it known that I, TONY ALEXANDER, a citizen of the United States, residing at Brookhaven, in the county of Lincoln and State of Mississippi, have invented certain new and useful Improvements in Levels, of which the following is a specification.

This invention relates to instruments designed chiefly for ascertaining horizontality and perpendicularity, the purpose being to provide in a single article means for attaining both ends or other predetermined angularity between the perpendicular and horizontal.

The invention consists of a hollow globe or sphere, preferably of glass, containing a liquid and an air-bubble adapted to be attached to a suitable frame, beam, or support and provided at determinate points with indicia, which in conjunction with said air-bubble determine the horizontal, vertical, or any determinate angular position.

For a full description of the invention and the merits thereof and also to acquire a knowledge of the details of construction of the means for effecting the result reference is to be had to the following description and accompanying drawings, in which—

Figure 1 is a perspective view of a hollow globe or sphere embodying the invention. Fig. 2 is a top plan view thereof. Fig. 3 is a vertical central section. Fig. 4 is a view similar to Fig. 3 of a modification.

Corresponding and like parts are referred to in the following description and indicated in all the views of the drawings by the same reference characters.

The globe or sphere 1 is hollow and preferably formed of glass and is provided with a neck 2 and base 3, the latter being preferably hollow upon its lower side to hold the neck 2 a short distance from the surface of the support, beam, or frame to which the globular body may be attached. The globe 1 is filled with a liquid, such as alcohol or spirits, with the exception of a minute space to provide the accustomed air-bubble 4 for indicating the level or other determinate position. A stopper 5 is fitted within the neck 2 and prevents escape of the liquid and may be adjusted to vary the size of the air-bubble as may be required by changes in temperature or by any possible loss of the liquid from any cause. The stopper 5 may be of any material, and its end projects beyond the neck 2 a distance to admit of it being conveniently gripped

when it is required to adjust the air-bubble to meet existing conditions. The projecting end of the stopper extends into the space of the hollow base 3 and is held out of contact thereby with the surface 6, to which the level device may be attached.

At determinate points in the surface of the globe or sphere indicia are provided, as indicated at 7. Each indice consists of a cross and a series of concentric circles, the centers of the cross and circles coinciding. The indicia are pressed in the surface of the globular body and are preferably formed in the inner surface, as shown most clearly in Fig. 3, although, as indicated in Fig. 4, they may be pressed or otherwise formed in the outer surface. By having the marks pressed into the inner surface of the globe the concavity is materially augmented and the sensitiveness of the level proportionately increased. By reason of the spherical shape of the body the air-bubble presents a rounded appearance and coincides with one or the other of the concentric circles, so as to accurately indicate the desired position. The indicia are located at the top and sides for designating perpendicular and horizontal lines and may be differently positioned if angles between the vertical and the horizontal are to be determined. This is an obvious application and may be readily comprehended.

In the modification shown in Fig. 4 each indice has a contrasting color from the body of the globe or sphere, and the cross and concentric circles are formed through the colored portion, so as to enable the bubble to be more readily located.

Having thus described the invention, what is claimed as new is—

1. In a leveling device, a hollow body of globular or spherical form filled with a liquid with the exception of a minute space forming an air-bubble, and having indicia at different points in its surface, each indice consisting of a series of concentric circles.

2. In a leveling device, a hollow body of globular or spherical form filled with a liquid with the exception of a minute space forming an air-bubble, and having indicia at different points in its surface, each indice consisting of a series of concentric circles, and a cross intersecting the lines of the circles and the centers of the cross and circles coinciding.

3. In a leveling device, a hollow body of spherical or globular form containing a liquid

and an air-bubble, and provided with indicia at different points in its surface and formed with a neck and a base, said base being hollow upon its under side and the neck adapted to receive a stopper, the end of which is adapted to project into the space of said hollow base.

4. In a leveling device, a hollow body of globular form having indicia pressed into its

inner surface to increase the concavity and containing liquid and an air-bubble.

In testimony whereof I affix my signature in presence of two witnesses.

TONY ALEXANDER. [L.S.]
